UNITED STATES PATENT OFFICE.

CHARLES HESS, OF BLOOMFIELD, NEW JERSEY.

DEVICE FOR AUTOMATICALLY BLOWING LOCOMOTIVE-WHISTLES.

SPECIFICATION forming part of Letters Patent No. 369,852, dated September 13, 1887.

Application filed February 4, 1887. Serial No. 226,547. (No model.)

To all whom it may concern:

Be it known that I, CHARLES HESS, of Bloomfield, in the county of Essex and State of New Jersey, have invented a new and Improved 5 Device for Automatically Blowing Locomotive-Whistles, of which the following is a full, clear, and exact description.

My invention relates to an improvement in devices for automatically blowing locomotive-whistles, and has for its object to provide a means whereby a whistle-signal may be given automatically just before reaching a station, or at any predetermined spot along the road, which signal may be of long or short 15 duration or intervals, as desired, and also to provide means whereby the signal may be given, as at present, without interfering with the automatic device.

The invention consists in the construction 20 and combination of the several parts, as will be hereinafter fully set forth, and pointed out in the claims.

Reference is to be had to the accompanying drawings, forming a part of this specification, 25 in which similar figures of reference indicate corresponding parts in both the views.

Figure 1 is a section through the cab of a locomotive, illustrating the application of my device when the valve is operated at the base 30 of the whistle; and Fig. 2, the application of the device to a whistle having the valve located at the top.

It is the aim of this invention to provide a device adapted for attachment to a locomotive, whereby a signal or series of signals may be automatically blown upon the whistle at any predetermined point, wherein the promptness of the engineer need not be relied upon to give warning, and wherein the said engineer 35 may be himself advised of an approach to a stopping place or point where a signal should be given.

To that end a block or series of blocks, 1, having downwardly-inclined ends 2 and a flat 45 face, 3, are secured inside the rail upon one or both sides of the track, to project slightly above the rail, which blocks may be of any desired length, number, or distance apart.

Beneath the cab of the locomotive a bracket, 50 4, is bolted, upon which a lever, 5, is centrally fulcrumed, having journaled in its lower end a wheel, 6. At one side of the bracket 4 a

spring, 6^a, is attached, adapted to bear upon the said lever 5 between its fulcrum and the wheel. Near the upper end of the lever 5 a 55 block, 7, having a beveled face, is attached to the under side of the cab, purposed to limit the upward movement of the lever. The position of the wheel 6 beneath the cab is in alignment centrally with the longitudinal axis 60 of the blocks.

Within the cab 8, near the floor, a second short lever, 9, is pivoted centrally its length horizontally to one side wall, which lever 9 is pivotally united at one end to the lower lever, 65 5, by a divided connecting-bar, 10, provided with a central attached spring, 11, the other end of the lever 9 being pivoted to a vertical connecting-bar, 12.

The connecting-bar 12 is provided a convenient 70 distance from its lower end with a longitudinal slot, 13, through which slot a thumb-screw is made to pass into a suitable socket secured in the side of the cab. The upper end of the connecting-bar 12 is passed up through 75 the cab-roof and pivoted to a horizontal lever, 14, fulcrumed centrally upon a stud attached to the roof. The free end of the said lever 14 is bent upward and outward at right angles to engage the end of an L-shaped bar, 15, attached to the under side of the whistle-valve lever 16, which lever, projecting beyond the connected L-shaped bar 15, is provided at its end with a rod, 17, leading through the roof into the cab, whereby the whistle-valve may be 80 85 opened in the ordinary manner.

Beneath the lever 14, near its pivoted connection with the bar 12, a block, 18, is attached to the cab to limit the downward movement of said lever 14, and beneath the forward end 90 95 of said lever 14, and beneath the forward end of said lever 14, a spring, 19, is placed, adapted to return the lever to its normal position.

In operation, as the wheel 6 engages the top surface of the block or blocks 1, a long, short, or intermittent blast of the whistle will be automatically given, according to the arrangement and length of said blocks, which is effected as follows: The pressure of the wheel upon the blocks bears down one end of the lever 5, whereupon action is imparted to the horizontal lever 9, and through the connecting-bar 12 to the operating-lever 14, which lever, pressing upon the L-shaped bar 15, bears down the whistle-lever 16, thereby opening the valve of 100

the whistle. As soon as the wheel 6 has passed off the block the springs 11 and 19 return the levers to their normal position. In the event the automatic attachment is not desired, the 5 thumb-screw passing through the slot in the connecting-bar 12 is screwed down upon the same, locking it securely to the side of the cab. When the wheel now strikes the blocks, the spring 11 will only operate.

10 For single-track roads the journal of the wheel 6 may be extended transversely the track and properly supported, and two wheels be employed; or a complete device may be attached at each side of the cab.

15 In Fig. 2 the attachment of the device with a whistle having its valve at the top is illustrated. In this connection the lever 5 is pivoted to a connecting-bar, 20, extending through the floor of the cab, having an attached spring, 20, the upper end of which spring is secured to a tube, 22, having a hand-pin at its upper end and a bayonet-slot, 23, in one side. Within the tube 22 one end of a vertical rod, 24, is entered, having an integral pin, 25, adapted 25 to slide in said slot. The upper end of the rod 24 is carried through the cab-roof and pivoted to a short lever, 30, fulcrumed thereon, which lever, by means of a cord, 26, passing under a pulley, 27, is connected with the whistle-valve lever 28. The said cord may be spliced and the spliced end 29 carried down in the cab, passing over a suitable pulley secured to the roof, whereby a signal may be given by hand.

In operation, when the attachment is em- 35 ployed, the pin 25 is made to enter the lower horizontal portion of the slot 23. When, however, it is desired to operate the whistle by hand only, the said pin travels in the vertical portion of said slot.

Having thus fully described my invention, what I claim as new, and desire to secure by Letters Patent, is—

1. The combination, with a lever, 5, pivoted beneath a locomotive, a vertical connecting-bar having spring-connection with said lever, and means of locking said connecting-bar, of a lever, 14, pivoted to said connecting-bar and to the top of the locomotive, and means for connecting said lever 14 with the lever operating 45 the whistle-valve, substantially in the manner and for the purpose herein set forth.

2. The combination, with a lever pivoted beneath a locomotive, a vertical connecting-bar having spring-connection with said lever, 55 means for locking said connecting-bar, a lever, 14, pivoted to said bar and to the top of the locomotive, and means for operating the whistle-lever from said lever 14, of blocks 1, having flat upper surfaces, 3, and inclined sides 2, 60 secured inside the railroad-rails, said blocks adapted to project above said rails, substantially as herein shown and described, and for the purpose herein set forth.

CHAS. HESS.
